UNITED STATES PATENT OFFICE.

WILLIAM C. DEVEREAUX, OF DETROIT, MICHIGAN.

DOOR-LATCH ASSEMBLY.

Original application filed June 7, 1926, Serial No. 114,361. Divided and this application filed June 20, 1927. Serial No. 200,079.

This invention relates generally to door handle assemblies and refers more particularly to the attachment of such assemblies to vehicle doors.

5 An object of the invention is to provide a door handle assembly in which the lock is anchored in such a manner that it would be practically impossible for an unauthorized person to remove the lock to gain access to 10 the inside of the vehicle.

With these and other objects in view, the invention resides in certain novel features of construction, combinations and arrangements of parts as will be more fully described and 15 particularly pointed out in the appended claims.

In the accompanying drawings:

Figure 1 is a longitudinal sectional view of my handle assembly.

20 Figure 2 is a section through a wooden pillar showing the handle assembly secured thereto.

Figure 3 is a section through a wooden pillar showing a modification of Figure 2.

25 Figure 4 is a cross section of an all metal pillar construction showing the handle assembly secured thereto.

Referring now to Figure 1 of the drawing, there is shown a door handle assembly 1 consisting of an outer shank 2 of hollow tubular 30 formation having the inner end thereof reduced as at 3 to receive a solid spindle 4, this spindle being preferably secured to the shank by a welding operation.

35 A detailed description of the handle assembly will not be given herein as such an assembly forms the subject matter of my co-pending application Ser. No. 114,361 filed June 7, 1926, the present application being a 40 division thereof. Therefore only those elements which are essential to the present invention will be enumerated herein.

Upon the shank 2 is rigidly mounted a handle tube 5 against which a loosely mounted 45 escutcheon plate 6 is adapted to abut. The shank is loosely mounted in a base plate 7 and as shown is adapted to be enclosed by the escutcheon plate 6. The inner end of the shank 2 also supports a cup-washer 8 while a coil spring 9 is adapted to encircle 50 the shank between the washer 8 and base

plate 7 and tends to retain the base plate against the inner surface of the escutcheon plate.

As will be noted, a standard lock cylinder 55 10 is retained within the shank 2 and is so associated with the spindle 4 that a rotation thereof within the shank will move a locking bolt 11 into engagement with openings in the escutcheon plate and shank and thereby lock the handle against rotary movement.

Referring now to Figure 2, it will be noted that a wooden pillar is designated at 12, being provided with a transversely extending 65 bore 13, the outer portion of which is of larger diameter than the inner portion, thereby forming shoulders 14.

Mounted on the spindle 4 is a flat washer 15 secured thereto in any suitable manner 70 and when the handle is inserted in the transverse bore, this washer will engage the shoulders 14 and rest thereon, preventing any further movement of the spindle within the bore.

75 It has been the practice in the past for unauthorized persons to unscrew the escutcheon plate so that it could be pulled out free from the framework to gain access to the lock mechanism. The present construction has 80 been designed to prevent the removal of the escutcheon plate and the subsequent tampering with the lock mechanism. As shown, this is accomplished by providing a screw 16 that is screwed into the pillar so that the 85 inner end thereof projects into the transverse bore just in advance of the washer 15, limiting the longitudinal movement thereof.

The base plate 7 is provided with recessed 90 bosses 17 located on either side of the shank 2, while the escutcheon plate is provided with corresponding countersunk recessed portions 18 fitting into the bosses as shown in Figure 1. As will be noted, the bosses are substantially thick and are received in correspondingly deep recesses 19, located in the pillar 12. The thickness of the bosses as compared with the limit of movement of the washer is such that should an unauthorized person attempt to remove the escutcheon plate, the washer 15 would strike against 95 the inner end of the screw 16 before the 100

bosses had cleared the recesses and thus prevent any further outward movement of the escutcheon plate and the subsequent removal of the same.

5 In Figure 3 is shown an arrangement similar to that disclosed in Figure 2, with the exception that a machine screw 20 provided with a squared end 21 is used in place of the wood screw shown in Figure 2.

10 In Figure 4 an all metal pillar construction is disclosed. A metallic strip 22 is secured to the panel 23 in any suitable manner and is provided with depressed portions 24 corresponding to the recesses 19 for receiving the bosses 17. Projecting at right angles from the strip 22 is an integral flange 25 to which a nut 26 is rigidly secured. A bolt 27 corresponding to the screws 16 and 20 is provided for engagement with the nut to 20 limit the movement of the spindle.

15 From the foregoing it will be apparent that an improved construction has been provided which will greatly facilitate the assembling of the shank and lock mechanism of an automobile door handle and also provide an arrangement of parts which will discourage tampering with the locking mechanism by an unauthorized person.

20 While it is believed that from the foregoing description, the nature and advantages of my invention will be readily apparent, I desire to have it understood that I do not limit myself to the specific construction herein shown and described and that such changes 35 may be resorted to when desired as fall within the scope of what is claimed.

30 What I claim as my invention is:

1. The combination with a door, of a handle assembly having a shank extending 40 transversely of said door, a projection on said shank, an element supported by said door and disposed in substantially parallel relation to the projection on said shank so as to be engaged thereby, for preventing the removal of said handle assembly from the door.

45 2. The combination with a door, of a handle assembly having a shank extending transversely of said door, a projection on said shank, and means for securing the handle assembly to the door including an element supported by said door and disposed in substantially parallel relation to the projection on said shank in advance thereof and adapted to be engaged thereby.

50 3. The combination with a pillar, of a handle assembly having a shank extending transversely of said pillar, a projection on said shank and an escutcheon plate having a projection engaging a recess in the pillar, and means for securing the handle assembly to the pillar including an element disposed in the pillar in substantially parallel relation to the projection on said shank so as to be engaged thereby, the distance between 55 said element and projection being less than

the length of the escutcheon projection, whereby the latter will be retained in the recess in said pillar.

4. The combination with a pillar, of a handle assembly having a shank extending 70 transversely of said pillar, a washer on said shank and a base plate having a boss engaging a recess in the pillar, and means for securing the handle assembly to the pillar including a rotatable element disposed in the 75 pillar, in substantially parallel relation to the washer aforesaid so as to be engaged thereby, the distance between said element and washer being less than the length of the base plate boss, whereby the latter will be 80 retained in the recess in said pillar.

5. The combination with a pillar provided with a transversely extending bore enlarged at its outer end, of a handle assembly having a shank located in said bore, a projection on 85 said shank seated in the enlarged portion of the bore, a base plate having a boss engaging a recess in the pillar, and means for securing the handle assembly to the pillar including an element disposed in the pillar and having an end projecting into the enlarged portion of the bore aforesaid in substantially 90 parallel relation to the projection on said shank so as to be engaged therewith, the distance between said element and projection 95 being less than the length of the base plate boss, whereby the latter will be retained in the recess in said pillar.

6. The combination with a pillar provided with a transversely extending bore enlarged 100 at its outer end, of a handle assembly having a shank located in said bore, a projection on said shank seated in the enlarged portion of the bore, and a base plate having a boss engaging a recess in the pillar, said pillar being provided with a bore communicating with and extending substantially transverse to the enlarged portion of the said first mentioned bore, and means for securing the handle assembly to the pillar including an 105 element disposed in said second mentioned bore and having an end projecting into the enlarged portion of the first mentioned bore in substantially parallel relation to the projection on said shank so as to be engaged thereby, the distance between said element and projection being less than the length of the base plate boss whereby the latter will be 110 retained in the recess in said pillar.

7. The combination with a door, of a handle assembly having a shank extending transversely of said door, a washer secured to said shank, and means for securing the handle assembly to the door including a rotatable element removably supported in said door 120 and disposed in substantially parallel relation to said washer so as to be engaged thereby, for preventing the removal of said handle assembly from the door.

8. The combination with a door pillar 130

provided with a transversely extending bore
enlarged at its outer end, of a handle assem-
bly having a shank located in said bore, a
projection on said shank seated in the en-
larged portion of the bore, and means for
securing the handle assembly to the pillar
including an element disposed in the pillar

and having an end projecting into the en-
larged portion of the bore aforesaid in sub-
stantially parallel relation to the projec-
tion on said shank so as to be engaged there-
by.

In testimony whereof I affix my signature.

WILLIAM C. DEVEREAUX.
